UNITED STATES PATENT OFFICE.

JOHN WILLIAM NASMITH, OF MANCHESTER, ENGLAND.

EVENING MECHANISM FOR COTTON-OPENING MACHINES.

SPECIFICATION forming part of Letters Patent No. 630,087, dated August 1, 1899.

Application filed June 8, 1898. Serial No. 682,923. (No model.)

To all whom it may concern:

Be it known that I, JOHN WILLIAM NASMITH, of Manchester, in the county of Lancaster, England, have invented certain new and useful Improvements in Evening Mechanism for Cotton - Opening and Similar Machines, of which the following is a specification.

My invention relates to the feed-regulating machinery ordinarily applied to scutching-machines.

It has for its object the provision of means whereby the speed of the feed-roller may be accurately and delicately differentiated, while at the same time the traverse of the belt on the feed-cones is facilitated and its frictional contact with the cones increased.

In carrying my said invention into effect I employ an epicyclic gear between the driven cone and the feed-roller, the construction of which is of such a nature that the work of driving the said roller is taken from the cone-belt. Under my invention the function of the cone mechanism is simply that of a regulator, and the belt is relieved from the greater part of the strain usually existing.

In order that my invention may be the more easily understood and the more readily carried into effect, I have hereunto appended a sheet of drawings, in which—

Figure 1 is a side elevation of the said mechanism. Fig. 2 is a vertical section of the differential mechanism. Fig. 3 is a side elevation showing a modification. Fig. 4 is an end elevation of the latter form.

The same reference characters indicate the same parts in all the figures.

Reference for the present is made to Figs. 1 and 2. I drive the cone B, which in the drawings is shown placed in a vertical position, from the side shaft A by means of bevel-wheels. I continue the side shaft A through the framing and fix upon its inner end a spur-pinion C, which gears with a wheel D, compounded with a bevel-wheel D'. A second shaft E is placed in the position shown, being suitably supported in fixings attached to the framing. On the shaft E a drum F revolves freely, the said drum having a long sleeve or boss F', extending to the outer end of the shaft E. On the boss of the drum F the wheel D D' revolves loosely, and the pinion G is fixed on said sleeve or boss, which thus con-

stitutes a shaft. This pinion is used as a change-pinion and can be readily removed and replaced when desired. By means of a 55 carrier-wheel H and the compound wheel I I' the motion of G is communicated to the wheel J, fixed on the axle of the feed-roller K. Instead of the spur-gearing for driving the roller I may use worm-gearing and a vertical shaft 60 or any other suitable gearing. The drum F has fixed into it a stud L', on which a bevel-pinion L freely rotates. I may use two pinions instead of one, if necessary, for the purpose of balancing the mechanism. The pinion L gears with the bevel-wheel D' and also with a second pinion M, fixed on the shaft E. On the other end of E is fastened the wheel N, gearing with a pinion O, fixed on the axle of the driven cone P. The gearing by which 65 the belt R is moved on the cones B P is that which is ordinarily employed and is actuated in the usual way from the pedal-levers generally used.

The action of the above mechanism is as 70 follows: The resistance to rotation of the feed-roller K tends to keep the drum F stationary, while the rotation of the wheel D from the side shaft A would rotate the wheels L M if M were free to rotate. The speed of rotation 75 of M is, however, regulated by the cone P through the wheels O N. The effect is that the drum F is slowly rotated at a velocity depending on the difference in the velocity of the wheels D and M, and its rotation is communicated to the feed-roller by the gearing G H I I'. The velocity given to the feed-roller obviously depends upon the relative speeds of the shafts A and E and the proportions of the various wheels. The normal 80 speed of the feed-roller varies usually from three to ten turns per minute, and the range of variation in its normal speed when set to rotate at any given velocity ordinarily involves a change in the velocity of the driven 85 cone of about two to one. When the feed-roller is driven directly from the cone, this variation has to be provided for by the difference in the diameters of the two ends of the cones; but when mechanism constructed according to my invention is employed the driven cone only requires to have its velocity varied in the proportion, approximately, of 90 seven to six. I do not bind myself to this 100

difference, because it is obvious that the proportion may be varied as desired. The effect of the diminution in the variable velocity of the cone is that I am enabled to similarly proportion the two ends of the cones, so that their profile is flatter, and the belt has therefore a better grip on the cone-pulleys.

The advantages to be derived from the use of my invention are that I remove the work of driving the feed-roller from the cone-belt and leave it only the work of regulating the velocity of the pinion M, the feed-roller being driven from the side shaft through the intermediate gearing. The belt is therefore more easily moved and the movements of the pedals are made much more readily and with less expenditure of power. This, combined with the reduction of the taper in the cone-pulleys giving a better grip to the strap, renders the work of regulation lighter and more easily effected.

In the embodiment of my invention shown in Figs. 3 and 4 I modify the construction of the differential gearing slightly without changing its principle of operation. Parts corresponding to those shown in Figs. 1 and 2 are designated by the same reference-letters. K is the feed-roller, on which is fixed the wheel J, connected by gears H I to the wheel G, which is fast on the shaft S. This shaft runs freely in its bearings and has fixed or cast to its center a transversal boss S', which is bored out for a stud L', so that when the shaft S revolves the axis of the stud must revolve bodily with it in a plane normal to the shaft. The stud L' is at liberty to rotate in its bearing and carries fixed on one end the bevel-pinion L, gearing on either side with the bevels M and D', which are cast, respectively, with the bevel N and the spur D. The gears M N and D D' are both loose on the shaft S, which corresponds to in connection with Figs. 1 and 2. The bevel N gears with a bevel O on the shaft of the driven cone P, and the spur D gears with a spur-pinion C, fixed on the shaft A. The latter rotates at a fixed regular speed and drives the cone B

also at a fixed regular speed. The cones B and P are connected, as usual, by the cone-belt 50 R, and the usual or any suitable devices are provided for shifting the belt. The speed of the shaft S, and therefore the speed of the feed-roller K, depends, as before, upon the difference in speed between the oppositely-revolving bevels M and D'. 55

I claim—

1. In a machine of the character specified, the combination with the cones B and P and the connecting-belt, of the driving-shaft A 60 having gear connection with cone B and having pinion C, the pinion O on the shaft of the cone P, differential gearing including gears D' and M, the former having gear connection with pinion C and the latter with pinion O, 65 an intermediate pinion meshing with gears D' and M and mounted on a shaft extending through one of the gears meshing therewith and adapted to be carried about the axis of gears D' and M under the influence of the 70 differential motion thereof, a feed-roller, and gearing connecting the latter with the support of the said intermediate pinion.

2. In a machine of the character specified, the combination with the cones B and P and the connecting-belt, of the driving-shaft A 75 having gear connection with cone B and having pinion C, the pinion O on the shaft of cone P, the shaft E having gear N meshing with pinion O and having pinion M, the drum 80 F loosely mounted on shaft E and having sleeve F', the gear-wheel D and pinion D' mounted on the sleeve F', the pinion L meshing with pinions M and D' and mounted on a suitable bearing carried by the drum F, the 85 gear D and pinion C being arranged to intermesh, a pinion G fixed on the sleeve of the drum, a feed-roller, and gearing connecting the latter with the pinion G, substantially as described. 90

In testimony whereof I have affixed my signature in presence of two witnesses.

JOHN WILLIAM NASMITH.
